APPARATUS FOR APPLYING ADHESIVE PREPARATIONS

Raymond J. O'Brien, Rutherford, N. J., and Eardley Hazell, New York, N. Y., assignors to The Naugatuck Chemical Company, Naugatuck, Conn., a corporation of Connecticut

Application November 18, 1930
Serial No. 496,550

12 Claims. (Cl. 154—1)

Our present invention relates to textile fabrics and more particularly to an improved method of and apparatus for applying adhesive preparations to pile rugs.

5 In the manufacture of rugs, particularly pile rugs, it has been found that a more durable product is obtained, if the pile fibers are embedded in latex or rubber composition, and various devices have been proposed for applying 10 such latex or rubber composition to the pile fabric, none of which, however, have been entirely successful. It is essential that the adhesive preparations such as latex be applied in such a manner as to penetrate sufficiently into the rug to 15 provide a firm bonding of the pile fibers, yet they must not penetrate so far as to show on the top of the finished pile fabric.

It is possible to have an adhesive preparation such as latex or a composition of rubber 20 that will require no after working when applied to the rug, but such compounds are liable to strike through the elements of the rug and a defective rug is the result. On the other hand, adhesive preparations may be made which will 25 not strike through the body of the rug, yet which do not penetrate the pile to the depth necessary to secure proper adhesion of the fibers to the adhesive and this also results in the production of an inferior product. We have found that the 30 best results are obtained by the use of a compound of a consistency which will not strike through the body of the rug, the rug being subsequently subjected to a working operation. This working operation incorporates the fibers of the 35 pile of the rug within the adhesive preparation without causing the same to show on the top of the finished rug.

In our present invention we have devised an improved method of and device for working a 40 pile rug with which has been incorporated an adhesive compound such as latex. In carrying out our invention, we preferably utilize a means of mechanically feeding the pile rug fibers at any desired speed and associate therewith a roll 45 which preferably rotates in a direction opposite to or against the direction of travel of the rug fibers, and which roll is provided with a working element or a plurality of working elements, such as a helically wound resilient member. This 50 roll with the working element or elements there-

on flexes and bends the fibers of the pile of the rug against the line of travel thereof and also laterally of the direction of such travel.

As above indicated if the latex or dispersion composition is thick and pasty it cannot ordinarily be used, as when applied with prior devices it does not sufficiently penetrate the pile. Our improved device makes it possible to use a pasty preparation of latex.

An object of our invention, therefore, is an improved method of applying adhesives to a rug.

Another object of our invention, therefore, is an improved adhesive applying and working device for pile rugs.

In the accompanying drawing, illustrating a preferred embodiment of our invention;

Figure 1 is a sectional side elevation;

Fig. 2 is a plan view of one end of the device shown in Fig. 1;

Fig. 3 is an enlarged sectional elevation of the massaging roll shown in Fig. 1; and

Fig. 4 is a detail of a pile rug fabric to which an adhesive composition has been applied by the device illustrated.

Referring to the drawing, 10 designates any suitable base on which are arranged, at either end, pairs of aligned bearings 11—11 and 12—12 and in these pairs of bearings are rotatably mounted shafts 13 and 14, respectively. The 80 shaft 13 extends outward beyond the bearings 11 at one end and to such extending end is secured a pulley 15 over which runs a belt 16 leading to any suitable source of power. On the shafts 13 and 14 are arranged conveyor rolls 17 and 18, respectively, and over these rolls runs a conveyor belt 19. This conveyor belt is preferably made of an endless fabric belt 20 on one face of which is arranged a plurality of parallelly arranged slats 21 of any suitable material, such as wood, 90 and secured to and extending outwardly from these slats 21 and at an angle thereto are teeth 22. The endless conveyor belt 19 is adapted to have its upper reach moved in the direction of the arrow shown in Fig. 1, and it will be noted 95 that such upper reach lies in a substantially horizontal plane.

Arranged above the endless conveyor 19 is a source of supply of pile material 23 such as a chute 24 which terminates at a point above the upper 100

reach of the endless conveyor 19 and adjacent to the roll 17 on the shaft 13 and by reference to Fig. 1, it will be noted that such pile material 23 is fed downwardly through the chute 24 and thence 5 on to the top reach of the endless conveyor 19, the teeth 22 acting to forcibly feed such pile material 23 onward in the direction of the arrow shown in Fig. 1. The endless conveyor belt 19 is of any suitable length and width and on each side thereof 10 is arranged a guard, or wall 25, preferably made of flexible material, so as to insure easy passage over the rolls 17 and 18. The height of the wall 25 is preferably slightly less than the height of the pile material 23.

15 Arranged above the endless conveyor 19 and adjacent to the delivery end of the chute 24 is an adhesive holding tank 26. This tank is connected by a pipe 27 to any suitable source of supply of air under pressure. On the lower end of the tank 20 27 is formed a delivery nozzle or orifice 28, which extends across the width of the endless conveyor 19. The tank 26 holds the adhesive compound 29 and by properly adjusting the size of the orifice 28 and the pressure lead to the tank through the pipe 27, the rate of flow of the adhesive compound 25 29 may be regulated so that the desired amount may be applied to the pile material 23 as it is continuously carried under the supply of adhesive preparation.

30 Secured to the base 10 on either side of the endless conveyor 19 and adjacent the tank 26 are bearing members 30, each provided with a vertically arranged slot 31 in which is slidably mounted a bearing block 32. In the bearing blocks 32 35 are aligned bearings in which are rotatably mounted a shaft 33, one end of which extends outwardly beyond the bearing block 32 and has secured thereto a pulley 34 over which runs a belt 35 leading from any suitable source of power. Secured to the shaft 33 and extending over the 40 entire width of the endless conveyor belt 19 is a roller 36, having mounted thereon helically wound working elements 37 of any suitable form and size. The shaft 33 is adapted to rotate in the direction 45 of the arrow shown in Fig. 3, which, it will be noted, is opposite to the direction of travel of the pile material 23 on the endless conveyor belt 19. Associated with the bearing blocks 32 in the bearing members 30 are means 97 utilized for adjusting the pressure on the pile material exerted by the roller 36. As the pile material 23 moves past the orifice 28 of the adhesive holding tank 26, it will move under the roller 36 when the working elements 37 will work the upper surface of the 50 pile material and the adhesive compound 29 deposited thereon, and such action will force the adhesive compound 29 from its position on top of the pile material 23 to a position just within the surface of such pile material, as clearly shown in Fig. 3. Underneath the upper reach of the conveyor 19 may be provided a platen 9, suitably supported as by brackets fixed to base 10.

55 Mounted on the base 10 adjacent to the roller 36 and on each side of the endless conveyor 19 are 60 pairs of standards 38 on which are adjustably mounted members 39, and these members support a frame 40 extending across the width of the endless conveyor 19. Secured to the frame 40 is a smoothing blade 41 and which acts to smooth the 65 upper surface of the adhesive covered pile material 23, in much the same manner as with a smoothing knife. This smoothing action tends not only to smooth the adhesive 29, but also tends to remove surplus adhesive from the pile.

70 Secured to the base 10 and extending upwardly 75 therefrom on either side of the endless conveyor 19 are bearing standards 42. Secured to the top of such bearing standards are bearing members 43 in which is rotatably mounted a shaft 44, and on such shaft may be placed a roll of backing material 45, such, for example, as a roll of jute backing. Secured to the base 10 on either side of the endless conveyor 19 and extending upwardly from the base are pairs of standards 46 and adjustably mounted on such standards are bearing members 47, in which is rotatably mounted a roll 48. Secured to and extending upwardly from the base 10 on either side of the endless conveyor 19 and adjacent the smoothing blade 41 are pairs of standards 49, and on each of these standards are adjustably mounted a bearing member 50. Rotatably mounted in the bearings 50 80 is a shaft 51 that has secured thereto a roll 52. The jute backing 45 passes from the roll, above referred to, and passes under the roll 47, over and under the roll 52 and is forced into engagement with the top surface of the pile material 23. To insure that the jute backing 45 is guided properly over the roll 52 and onto the pile material 23, we have provided on the base 10 on either side 85 of the endless conveyor 19 and adjacent to the roll 52, pairs of standards 53 and on these standards are adjustably mounted holding devices 54 connected by a shaft 55. These holding devices 90 54 have secured thereto side guard plates 56 which engage with the edges of the jute backing 45 and insure the proper delivery thereof from the roll 47 to the roll 52. Between the pair of standards 46 and 53 and on the base 10 are arranged pairs of standards 57 and on these pairs of standards 95 are adjustably mounted bearing members 58. Adjustably mounted in the bearing members 58 is a shaft 59 on which is mounted a bar 60 having secured to its under face a cement-applying blade 61. Also adjustably mounted on the pairs 100 of standards 57 are members 62 connected by a shaft 63 and on which shaft is a bar 64. On the pairs of standards 46 are adjustably mounted members 69 on which are arranged a shaft 66 carrying a bar 67. The bars 64 and 67 act as supports for a table 68 that supports the jute backing 45 in its passage from the roll 57 to the roll 52 and also the table 68 cooperates with the blade 61 to form a receptacle for a body of cement 70 or for any other suitable adhesive. The jute 105 backing 45 passes from the roll under the roll 47 over the table 68 and under the blade 61, is coated with adhesive 70 and so is in prime condition to adhere to the upper surface of the adhesively covered upper surface of the pile material 23. 110

115 After passing under the roll 52 so as to have the jute backing 45 attached thereto, the pile material 23 is carried by the endless conveyor belt 19 into a vulcanizing oven 71. This vulcanizing oven is of any suitable length to have the vulcanized operation carried out on the unvulcanized adhesive material 29 and in order to supply heat to such oven, we mount on the base 10 an air heating device 72 on top of which is mounted a blower 73, driven from any suitable source of 115 power, as by electric current, and the heated air is blown through the pipe 74 and into the oven 71, passing through the length of the oven and is exhausted out of the orifices 75. Within the oven 71 are arranged above the endless conveyor belt 145 19, a plurality of parallelly arranged ironing rolls 76, and by means of which the jute backing 45 is rolled into firm engagement with the pile material 23. After passing through the vulcanizing oven 71, the treated pile fabric is rolled onto 150

an arbor 77, suitably supported by any convenient means.

For economy in manufacture, the pile material 23 is preferably made twice the thickness of the ordinary rug, and, therefore, such pile material 23 is preferably run twice through the apparatus, as above described, or twice through equivalent apparatus in order to have the adhesive compound 29 applied to and worked into both surfaces thereof, and also to have a backing 45 attached to both sides. The resultant product is shown in cross-section in Fig. 4, and such product may be conveniently and by any of the usual and well-known means split into two parts along approximately the line 78. Each half of the pile fabric, as shown in Fig. 4, may thus constitute a rug or other floor covering. If desired, during the operations above described, that of applying the jute backing may be omitted, and after splitting, as above immediately described, the two halves of the structure may be placed back-to-back and be adhesively united together, the result being a double-faced pile fabric.

While we have necessarily shown and described the preferred embodiment of our invention on somewhat in detail, it is to be understood that we are not to be limited to the exact structure shown and may vary the size, shape and arrangement of parts comprising the device within relatively wide limits without departing from the spirit and scope of the invention.

Having thus described our invention, what we claim and desire to protect by Letters Patent is:

1. In an improved device for applying an adhesive preparation to pile materials, the combination of a source of supply of parallelly arranged fibers, a source of supply of adhesive preparation in paste form, means for feeding the parallelly arranged fibers continuously in the form of a flat layer into association with the source of supply of adhesive preparation to thereby have a layer of the adhesive preparation deposited on the layer of parallelly arranged fibers, and means for bending and flexing the fibers to work the adhesive preparation into the surface of the layer of fibers and around the fibers.

2. In an improved device for applying an adhesive paste to pile materials, the combination of a source of parallelly arranged fibers in the form of a flat layer, means for continuously advancing such layer, means for depositing an adhesive paste on one face of said layer, and means for bending and flexing the fibers to work the adhesive paste into the surface of the layer and around the fibers thereof.

3. In an improved device for applying an adhesive paste to pile materials, the combination of a source of parallelly arranged fibers in the form of a flat layer, means for continuously advancing such layer, means for depositing an adhesive paste on one face of said layer, means for bending and flexing the fibers to work the adhesive paste into the surface of the layer and around the fibers thereof, and means for attaching a backing to the face of the layer.

4. In an improved device for applying an adhesive paste to pile materials, the combination of a source of parallelly arranged fibers in the form of a flat layer, means for continuously advancing such layer, means for depositing an adhesive paste on one face of said layer, means for bending and flexing the fibers to work the adhesive paste into the surface of the layer and around the fibers thereof, means for attaching a backing to the face of the layer, and

means for forcing said backing into intimate engagement with the adhesive paste.

5. In an improved device for applying an adhesive paste to pile materials, the combination of a source of parallelly arranged fibers in the form of a flat layer, means for continuously advancing such layer, means for depositing an adhesive paste on one face of said layer, means for bending and flexing the fibers to work the adhesive paste into the surface of the layer and around the fibers thereof, means for attaching a backing to the face of the layer, means for forcing said backing into intimate engagement with the adhesive paste, and means for vulcanizing said adhesive paste.

6. In an improved device for applying an adhesive paste to pile materials, the combination of a source of parallelly arranged fibers, in the form of a flat layer, means for advancing said layer continuously, means for depositing an adhesive paste on one face of said layer, and means for bending and flexing the fibers to work the adhesive paste into the surface of the layer and around the fibers thereof.

7. In an improved device for applying an adhesive paste to pile materials, the combination of a source of parallelly arranged fibers, in the form of a flat layer, means for depositing an adhesive paste on one face of said layer, means for bending and flexing the fibers to work the adhesive paste into the surface of the layer and around the fibers thereof, and means for imparting a continuous relative movement between the layer of fibers and the bending and flexing means.

8. In an improved device for applying adhesive preparations to pile materials, the combination of a continuously advancing conveyor, a roller located above the conveyor and rotatable in a direction opposite to the direction of travel of the conveyor and a platen supporting the upper surface of the conveyor at a point opposite the roller.

9. In an improved device for applying adhesive preparations to pile materials, the combination of a feeding conveyor for feeding such material, a platen supporting the upper reach thereof in a horizontal plane, a roller located above the conveyor, a helically arranged working element on the roller and associated with the conveyor, and means for rotating the roller to have the helically arranged element exert a working action on the pile material.

10. In an improved device for applying adhesive preparations to pile materials, the combination of means for continuously advancing pile material, an adhesive paste feeding means for spreading paste on the surface of a layer of the pile material, and a working device cooperating with the said first mentioned means, and means for imparting motion thereto in a direction opposite to the direction of travel of the pile fabric.

11. In an improved device for applying adhesive preparations to pile materials, the combination of a feeding conveyor for feeding such material, a roller located above the conveyor and rotatable in a direction opposite to the direction of travel of the conveyor, an adhesive paste feeding means for spreading paste on the surface of the pile material, a working device on the roller cooperating with the conveyor, and a platen supporting the upper surface of the conveyor at a point opposite the roller.

12. In an improved device for applying ad-
